UNITED STATES PATENT OFFICE

2,571,225

FRICTIONAL CAR TRUCK BOLSTER

Louis E. Endsley, Pittsburgh, Pa., assignor to The
Frost Railway Supply Co., Detroit, Mich., a
corporation of Michigan

Application August 16, 1949, Serial No. 110,594

2 Claims. (Cl. 105—197)

1

My invention relates to railway car trucks, and more particularly to that type having "swing motion" bolsters, the present invention comprising an improvement on that of my Patent Number 2,466,088 issued April 5, 1949.

In said patent wedges are employed for placing and holding the snubbing springs in compression against the friction shoes that dampen vertical movements of the bolster on the truck frame.

In the present case I employ a simpler and more conveniently operable means for placing the snubbing springs under compression, the said means comprising a shaft having a cam that is rotatable to place the springs under compression and release them, the shaft and its cam being more easily removed from the bolster than are the wedges of said patent, thus facilitating the disassembly and reassembly of the snubbing elements when replacements or repairs are required.

Certain features of this invention, and particularly the rotatable camming device for the snubbing springs can be used with forms of truck frames other than that shown in the drawing of this application.

In the accompanying drawing, Fig. 1 is a plan view of a portion of a truck bolster and truck frame equipped with my invention; Fig. 2 is an enlarged view taken on the line II—II of Fig. 1; Fig. 3 is a view taken on the line of III—III of Fig. 1; Fig. 4 is a side view of the cam shaft for placing the snubbing springs under compression and Figs. 5, 6, and 7 are views taken on the lines V—V, VI—VI and VII—VII, respectively, of Fig. 4.

Substantially all of the parts of the structure, except for the tensioning cam for the snubbing springs, are as shown in my said patent and therefore need not be described in detail. The device is shown as applied to a truck bolster 10 having divided or bifurcated arms 11 that extend past the vertical guide columns 12 of a car truck frame. The truck frame carries the usual springs 13 and 14 for supporting the bolster.

Friction shoes 15 and 16 are slidably supported at their ends in grooves 17 in the arms 11 of the bolster and are in vertical sliding frictional engagement with the bolster columns 12 during vertical movements of the bolster through compression and relief of load on the springs 13—14.

Snubber springs 18 and 19 are interposed between the friction shoe 15 and a spring seat 18a, and between the shoe 16 and a spring seat 20. The seats 18a and 20 have reduced ends that slide in the grooves 17, so that they will have some longitudinal movement therein and can be con-

2

veniently slid into and out of place at the end of the bolster, when a retaining block 21 is removed as explained in my said patent.

In order to place the springs 18—19 under compression, to thereby hold the shoes 15—16 in frictional engagement with the guide columns 12, I employ a cam shaft 22 that extends through the bolster arms at a point between the spring seats 18a—20. The shaft is rotatable in the bolster and has a median flattened camming section 23 that will be turned to compress the springs 18—19 and to release them. As shown in Fig. 2, the wide section of the cam is in position holding the spring seats 18a—20 spread apart to compress the snubber springs 18—19 and to thereby hold the shoes 15—16 in frictional engagement with the guide columns of the truck frame. When the shaft 22 is turned 90 degrees from the position shown in Fig. 2, the spring seats will be released and the springs 18—19 can conveniently be lifted from the bolster to permit replacements thereof.

To prevent accidental turning of the shaft 22 from its operative position, I provide a cotter pin 24 that extends through holes in bosses 25 on the side of the bolster and through a hole 26 in the shaft.

The cam shaft can be formed from a two-inch round rod, for example, the rod being forged at its mid-portion, and its ends shaped for a wrench.

30 I claim as my invention:

1. The combination with a railway car truck side-frame which has a pair of vertical guide columns that are spaced apart in directions transversely of the frame, of a truck bolster having arms extending across the front and rear sides of the columns, springs for yieldably supporting the bolster on the truck frame, friction shoes disposed between the said arms and the pair of guide columns and each shoe having frictional engagement with the adjacent surface of a column and movable vertically thereon, a pair of spring seats, a snubbing spring interposed between each seat and one of the shoes, means on the bolster arms for supporting the shoes and the spring seats against vertical movement relative to the bolster and for supporting the shoes and seats for movement longitudinally of the bolster, and a cam shaft extending through the said arms and having a cam near its mid portion, positioned to move the spring seats apart through rotation of the shaft, to thereby place the snubbing springs under compression.

2. The combination with a railway car truck side-frame which has a pair of vertical guide columns that are spaced apart, of a truck bolster

having vertically slidable connection with the columns, springs for yieldably supporting the bolster on the truck frame, friction shoes carried by the bolster at points between the guide columns and each shoe having frictional engagement with the adjacent surface of a column and moveable vertically thereon, a pair of spring seats between the shoes, a snubbing spring interposed between each seat and one of the shoes, means on the bolster for supporting the shoes and the spring seats against vertical movement relative to the bolster and for supporting the shoes and seats for movement horizontally on the bolster, and a rotatable horizontal cam shaft carried by the bolster and with an extension accessible at one vertical face of the bolster and having a cam

interposed between the seats, for moving the seats apart and thereby placing the snubbing springs under compression upon rotation of the extension of the shaft.
